UNITED STATES PATENT OFFICE.

EMILIE WOLFGANG, OF BERLIN, GERMANY.

COMBINED WARDROBE AND TRAVELING-TRUNK.

SPECIFICATION forming part of Letters Patent No. 691,518, dated January 21, 1902.

Application filed August 12, 1901. Serial No. 71,785. (No model.)

To all whom it may concern:

Be it known that I, EMILIE WOLFGANG, a subject of the German Emperor, residing and having my post-office address at Neuen-
5 burgerstrasse 35th, Berlin, Germany, have in-
vented certain new and useful Improvements
in a Combined Wardrobe and Traveling-
Trunk, of which the following is a specifica-
tion.

10 The present invention relates to a wardrobe
adapted to be used as a traveling-trunk, in
which clothes, linen, and the like are so ar-
ranged that on tilting up the said wardrobe
in order to convert it into a traveling-trunk
15 the articles contained therein do not become
mixed or press undesirably upon each other.

20 The arrangement of a traveling-trunk in
such a manner that on arriving at its desti-
nation the said trunk is placed on its narrow
25 side or otherwise to be used as a cupboard
or wardrobe or chest of drawers is, broadly
speaking, not new. However, similar con-
structions hitherto used have had such dis-
advantages that they were very little used by
30 travelers, chiefly on account of the fact that
clothes, linen, and other articles were not so
arranged that they could be easily taken out
and put back again, but could only be taken
35 out after the complicated removal of a frame,
and, further, that in using the said wardrobe
as a traveling-trunk the articles contained
therein were not securely arranged and were
40 consequently apt to press on each other and
to become mixed. Especially for more ex-
pensive ladies' and gentlemen's clothing this
is of great disadvantage, in consequence of
which travelers have hitherto preferred ordi-
45 nary traveling-trunks with inserted frames,
in which the more expensive clothes are
loosely arranged.

According to the present invention the com-
bined wardrobe and traveling-trunk contains
a compartment for clothes and another for
linen, in which compartments the various ar-
45 ticles are visible at a glance and can thus be
identified and taken out at once. When
traveling, the said articles are so arranged
that they cannot press upon each other or be-
come mixed. The lower part of the traveling-
50 trunk forms one compartment, which may be
called a "hanging-compartment," for clothes,
sticks, umbrellas, and the like, while its cover

forms the other compartment, of the nature
of a cupboard, for linen, and at the same time
is provided with drawers for boots, shoes, 55
hats, and similar articles.

The manner of arranging clothes, linen,
and the like in the traveling-trunk so as to
protect them from becoming mixed and crum-
pled is shown in the annexed drawings. 60

Figure 1 shows a view of the open wardrobe
standing upright with the doors of the cup-
board for reception of linen opened. Fig. 2
is a section of Fig. 1 on the line A A, the cup-
board being closed. Fig. 3 is a section on 65
line B B of Fig. 1 through the open wardrobe,
but with the doors of the linen-cupboard
opened. Fig. 4 shows a longitudinal section
through the closed wardrobe, showing the
manner of inserting articles of clothing. 70
Figs. 5, 6, and 7 show a form of construction
of an arrangement for fixing the clothes-hold-
ers—Fig. 5 in longitudinal section, and Fig. 6
in elevation in opened and Fig. 7 in closed po-
sition. Figs. 8 and 9 show views of the mech- 75
anism for opening and closing the said fixing
arrangement—Fig. 8 in opened and Fig. 9 in
closed position.

In Figs. 1 to 3, 1 represents the hanging-
compartment, containing a cross-bar 2 for sus- 80
pension of the clothes-holders 10 and arranged
fairly close to the upper wall. It may also
be provided with side pockets 8 and springs
or straps 9, arranged in the corners for hold- 85
ing sticks and umbrellas. The linen-cup-
board contains open shelves 4 and drawers 5.
Its shelves are closed by doors 6, which at the
same time secure the drawers from opening.
In order to prevent the linen from becoming 90
mixed, bands 7, provided with buckles, are
arranged on the shelves, so that by means of
said bands the linen can be fastened to the
shelves. On the lower side of the shelves are
hooks 8^a, over which the bands may be hung
when packing. 95

The clothes-holders, which are of special
construction, and an arrangement for fixing
same to the rod 2, from which they are sus-
pended, serve to maintain the clothes in their
position on the journey and to prevent them 100
from becoming mixed. A clothes-holder of
this description is shown in Fig. 4, which at
the same time shows its position in the trunk.

The new clothes-holder differs from those

hitherto known in the fact that in addition to a trousers-holder or cross-bar 11 it is provided with a frame 12, occupying the whole length of a coat, which frame is provided with bands 5 carrying fasteners 13, by means of which long garments can be held in place. At the same time the clothes-holder, movable on and suspended from the rod 2, before mentioned, can be fixed in position thereon by means of a 10 mechanical fixing arrangement, and, if required, can also be firmly connected with another cross-bar, string, band, or the like 14, Fig. 1, at the opposite or lower end of the compartment by means of one of the fasteners 15. By means of these arrangements the garments are so kept that the separate pieces cannot get entangled or mixed no matter on what side the trunk is tilted. The clothes 20 can be easily put over the holder-frame and are thus well protected, and since the clothes can always be put back on the said holder-frame after use the trouble of packing the trunk is removed. This arrangement of the 25 traveling-trunk is of a special advantage, since it considerably facilitates the revision of the contents at the custom-house. On opening the trunk put up so as to serve as a wardrobe the customs officials can easily see the contents, and the troublesome ransacking of 30 the trunk is thus removed.

The mechanical arrangement of fixing the clothes-holder to the rod on which it was previously movable can be made in different ways. A practical arrangement of this kind 35 is shown in Figs. 5 to 9. The cross-bar 2 consists of a tube which has a slot-shaped opening above. (See Figs. 8 and 9.) It is fixed to the end plate 17, the said end plate being fixed to the wall of the 40 trunk, as shown in Fig. 1. Above the stationary cross-bar 2 is a vertically-movable comb-shaped rod 3, which when lowered locks or holds the hooks of all the clothes-holders in the positions they respectively occupy at 45 that moment. The lifting or lowering and manner of fixing the said rod 3 can be easily seen from the drawings. In a branch tube 15 from the cross-bar 2 there moves a rod 18, which can be moved to and fro in said tube 50 by means of a button 19, passing through an angular slot 20, said rod being kept in tension by means of two springs 21 and 22. When the button 19 is moved upward into the up-

per part of the slot 20, the spring 22 presses the bar 3 downward, while on the button being moved into the lower part of the slot the spring 21 presses the bar upward, the latter thus remaining fixed in both cases. 55

The combined wardrobe and trunk described above may be suitably used as a sample-trunk for commercial travelers, who can thus more easily show the goods to their customers. According to the nature of the goods, both sides of the trunk may then be made as a hanging-compartment or as a cupboard provided with a suitable number of shelves. 60 65

What I claim is—

1. A combined wardrobe and traveling-trunk comprising in combination a main part constituting a hanging-compartment and a lid 70 part constituting a cupboard-compartment, clothes-holders in said hanging-compartment, consisting of frames and provided with means for holding the clothes thereon, a slotted cross-bar for supporting said holders, a comb-like 75 or serrated bar adapted to enter said slotted cross-bar for securing the holders in position, means for locking said serrated bar in its upper or lower position, shelves and drawers in said cupboard-compartment, means for securing articles on said shelves, and doors for closing both shelves and drawers, substantially 80 as described.

2. A combined wardrobe and traveling-trunk comprising in combination a main part 85 constituting a hanging-compartment and a lid part constituting a cupboard-compartment, clothes-holders in said hanging-compartment, consisting of frames and having bands or straps provided with fasteners for securing 90 the clothes on said holders, a slotted cross-bar for supporting said holders, a comb-like or serrated bar adapted to enter said slotted cross-bar for securing the holders in position, means for locking said serrated bar in its upper or lower position, shelves and drawers in 95 said cupboard-compartment, straps or bands for securing articles on said shelves and doors for closing both shelves and drawers, substantially as described. 100

In witness whereof I have signed this specification in the presence of two witnesses.

EMILIE WOLFGANG.
